DESIGN.

No. 33,206.

Patented Sept. 18, 1900.

G. STOCKER.

CANE.

(Application filed Aug. 24, 1900.)

UNITED STATES PATENT OFFICE.

GEORGE STOCKER, OF NORTH PASADENA, CALIFORNIA.

DESIGN FOR A CANE.

SPECIFICATION forming part of Design No. 33,206, dated September 18, 1900.

Application filed August 24, 1900. Serial No. 27,961. Term of patent 14 years.

To all whom it may concern:

Be it known that I, GEORGE STOCKER, a citizen of the United States, residing at North Pasadena, in the county of Los Angeles and State of California, have invented and produced a new and original Design for Canes, of which the following is a specification, reference being had to the accompanying drawings, forming a part thereof.

10 Figure I is a view of a cane, showing my new design. Fig. II is a fragmental view of the same on a larger scale. Fig. III is a plan of the head or knob of the cane.

15 As shown in the drawings, the leading or material feature of my design for a cane consists of a star-spangled knob or head *a* and a striped body *b*.

1 indicates the field of the head, and 2 indicates the stars in said field.

3 indicates stripes of one color—red, for example—and 4 indicates stripes of another color—white, for example—distinguished from the other stripes.

Having described my invention, what I claim as new, and desire to secure by Letters Patent of the United States, is—

The design for a cane, as herein shown and described.

In testimony whereof I have signed my name to this specification, in the presence of two subscribing witnesses, at Los Angeles, California, this 18th day of August, 1900.

GEORGE STOCKER.

Witnesses:

JOHN A. MORRIS,
JAMES R. TOWNSEND.
